UNITED STATES PATENT OFFICE.

HENRY LANGE, OF QUINCY, ILLINOIS.

HEATER.

Application filed January 6, 1927. Serial No. 159,403.

The present invention relates to heaters, and aims to provide a novel and improved air circulating heater to be used within a room.

One object of the invention is the provision 5 of an air heater comprising a stove and a casing surrounding same, in order that the casing will conceal the stove from view as well as forming an air heating chamber between the stove and casing, said casing providing 10 an ornate and attractive appearance so that the heater will not be as objectionable in a living room or elsewhere as the ordinary heating stove.

Another object of the invention is to provide 15 a heater of the kind indicated comprising a casing which simulates a fireplace so as to be attractive and appropriate for the purpose for which it is used.

A further object of the invention is the provision 20 of such a heater whose casing has doors which conceal the stove when the doors are closed, and which when opened permit the stove to be tended in the usual manner, with novel means for latching the doors closed and 25 limiting the opening movement thereof.

A still further object of the invention is the provision of a heater of the character indicated which is improved generally in its construction, assembly and details to obtain 30 beneficial advantages as will hereinafter more fully appear.

With the foregoing and other objects in view, which will be apparent as the description proceeds, the invention resides in the construction 35 and arrangement of parts, as hereinafter described and claimed, it being understood that changes can be made within the scope of what is claimed, without departing from the spirit of the invention.

The invention is illustrated in the accompanying drawings, wherein—

Figure 1 is a perspective view of the improved heater.

Fig. 2 is a front view thereof with the doors 45 swung open as when tending the stove.

Fig. 3 is a vertical section on the line 3—3 of Fig. 2, with the doors closed, and the stove shown in elevation excepting the lower end portion thereof.

Fig. 4 is a section on the line 4—4 of Fig. 3.

Fig. 5 is a plan view of the stand and the base plate of the stove seated thereon.

Figs. 6 and 7 are enlarged sectional details 50 on the lines 6—6 and 7—7, respectively, of Fig. 4.

A stand is provided on which the stove

and surrounding casing are mounted, and this stand comprises legs 11 at the four corners, a front member 12, side members 13 and a rear member 14, all preferably composed of metal 60 castings. The legs 11 are of angular cross-section and the members 12, 13 and 14 overlap the flanges thereof within the legs and are bolted, as at 15, or otherwise secured to said legs, thus providing a substantial rectangular frame, with said members spaced above the floor on which the legs seat. The frame members 12, 13 and 14 of the stand 65 have inwardly extending flanges 16 at their upper edges forming a seat for the stove and casing.

The stove comprises a base plate 17 of cast metal having at its side and rear edges the depending flanges 18 bearing on the flanges or seats 16 of the members 13 and 14, said 70 flanges having the upstanding lips or secondary flanges 19 at the inner sides of the flanges 18, to prevent the stove and casing from shifting out of position on the stand. The stove also includes the ashpit 20 having the lower outwardly extending flange 21 at its sides and back seated on the base plate 17 and secured thereto by bolts or otherwise. The ashpit 20 has the door 22 at the front 75 thereof similar to the ordinary stove, and the front wall of the ashpit has a cross bar 23 below the ash door opening which seats on a downwardly offset portion 24 along the forward edge of the plate 17. The portion 24 seats on the flange 16 of the member 12 80 and forms a shoulder or abutment 26 on the plate 17 immediately behind the bar 23. The plate 17 has a dropped portion 25 below the ashpit and forming the bottom thereof, on which the ash pan is seated, and the forward 85 end of the portion 25 is inclined in order that ashes may be readily scraped out of the ashpit over the bar 23.

The stove is of conventional construction in that it has a firepot 27 above the ashpit 20, and a combustion chamber 28 above the firepot 27, with a front door 29 which may be opened for depositing the coal or other fuel in the stove, and the combustion chamber 28 has a cast metal outlet member 30 extending rearwardly for the connection of the stove pipe which may lead directly rearwardly or upwardly to the chimney. The stove, including the base plate 17, is seated removably on the stand, and the weight of the ashpit 20, 100 firepot 27 and combustion chamber 28 is imposed on the plate 17.

- The casing which surrounds the stove is of rectangular outline to correspond to the base plate 17 and stand, and includes the front and rear corner members 32 and 33, respectively, which are of angular cross-section. The front wall of the casing includes the members 32 and an upper plate or member 34 extending over the door opening between the members 32. The sides of the casing comprise in connection with the members 32 and 33, upper and lower cross members 35 and 36 and sheet metal panels 37 having their edges overlapping and bolted or otherwise secured to the members 32, 33, 35 and 36.
- 10 The rear wall of the casing comprises with the members 33 upper and lower cross members 38 and 39, respectively, and a sheet metal panel 40 having its edges overlapping and bolted or otherwise secured to the members 33, 38 and 39. The members 32, 33, 34, 35, 36, 38 and 39 are of cast metal and said members are bolted or otherwise secured together in any well known manner to provide a rigid construction.
- 15 The back panel 40 has an upper opening 41 through which the outlet member 30 of the stove extends, and a cast metal frame 42 is preferably secured to the panel around the opening 41. Said panel has a lower opening 43 behind the ashpit 20 and firepot 27 for the reception of a pan or receptacle (not shown) containing water in order that the water will be heated and evaporated to supply moisture to the air heated by the stove. A cast metal frame 44 is secured to the panel 40 around the opening 43. It is also preferable to provide a horizontal stiffening rib 45 for the panel 40 intermediate the upper and lower openings 41 and 43.
- 20 One side panel 37 has a pivoted closure 46 normally covering an opening in said panel in order that when said closure is swung in either direction it will expose a shaker portion 47 projecting from the corresponding side of the stove, in order that the bottom grate of the firepot may be rocked for shaking down the ashes.
- 25 The casing is supported by and secured to the base plate 17 of the stove, so that they may be handled as a single unit. Thus, the rear flange 18 of the plate 17 and lower back wall member 39 are clamped together by means of bolts 48 located below the plate 17, said plate having raised portions 49 to accommodate said bolts, as seen in Fig. 6. The members 36 and 39 have inwardly extending lugs 50 seating on the plate 17 in order to support the casing from the plate 17. The front corner members 32 have inwardly extending ears 51 at their lower ends seating on and bolted or otherwise secured to the plate 17.
- 30 The casing is spaced from the stove to provide an air chamber surrounding the stove within the casing, and the ashpit 20 is spaced from the walls of the casing, and the plate

17 is provided with air inlet openings 52, between said ashpit and casing walls in order that air may flow upwardly from within the stand, the stand being open within the outline of the members 12, 13 and 14 thereof. 70

Grids or grating plates 52' are provided to form a top for the casing having openings therein for the upward discharge of the heated air from the casing, and not only provide a suitable finish for the upper portion of the casing, but also prevent objects from falling down into the casing as well as enabling objects to be seated on the casing. The front and rear members 34 and 38 of the front and back walls of the casing have inwardly extending lugs 53 on which the grids 52' are seated and to which they may be fastened by bolts or other securing elements.

Doors 54, which are preferably of cast metal, are provided to close the door opening in the front wall of the casing, and are hinged at their opposite edges, as at 55, to the casing at the opposite edges of the door opening, so that said doors may swing open outwardly away from one another. 85

In order to hold said doors in closed position a cross bar 56 extends across the opening behind the doors and has its terminals bolted or otherwise fastened, as at 57, to the members 32, and handles or knobs 58 are mounted for rotation in the doors at the adjacent edges thereof and have hooks or latches 59 in back of the doors to engage behind the intermediate portion of the bar 56, in order to hold the doors closed tightly. The bar 56 and latches are located intermediate the doors 22 and 29 of the stove so that said bar will not interfere with the opening of the stove doors when the casing doors 54 are swung open as seen in Fig. 2, and when the doors 54 are closed they conceal the stove doors, so that no part of the stove proper is disposed to view. The bar 56 is curved rearwardly, as at 60, adjacent to its ends, behind the opposite edges of the doors 54, to permit said edges to swing in rear of the vertical axes of the hinges 55, and the bar 56 has forwardly extending stop lugs 61 for the contact of the hinged edges of the doors 54, in order to limit the swinging movement of said doors when opened. This will relieve other parts of the structure from strains and shocks when the doors 54 are swung open, and will avoid damage to the exterior finish of the casing and doors 54. 110

The outer surface of the legs and members of the stand and members 32, 33, 34, 35, 36, 38 and 39 of the casing are finished in order that the casing resembles a fireplace in appearance, which adds considerable to the desirability and utility of the heater in a living room, and instead of being more or less unsightly like the ordinary heating stove the present heater is attractive and pleasing in appearance so as to be more desirable. Said 125

parts or members are formed with grooves and offset portions so as to define brick faces, to give the appearance of brickwork, in order that the casing will give the impression of 5 being built up of bricks like a fireplace. The outer surfaces of said parts or members are given a sandy brick- or tile-like appearance according to the manner of ornamentation as disclosed in my copending application Serial 10 No. 108,180, filed May 10, 1926. Thus, the portion of the stove surrounding the door opening has an appearance closely simulating a fireplace composed of brickwork.

Having thus described the invention, what 15 is claimed as new is:—

1. A heater comprising a stove having a fuel door and an ashpit door, a casing surrounding the stove and having an opening to expose said doors, a pair of doors hingedly 20 mounted at the opposite side edges of said opening of the casing, a bar extending across said opening intermediate said fuel and ashpit doors and having its terminals secured to the casing behind the edge portions thereof 25 at said opening, and means for latching said pair of doors to said bar.

2. A heater comprising a stove having a fuel door and an ashpit door, a casing surrounding the stove and having an opening to

expose said doors, a pair of doors hingedly 30 mounted at the opposite side edges of said opening of the casing, a bar extending across said opening intermediate said fuel and ashpit doors and having its terminals secured to the casing behind the edge portions thereof 35 at said opening, and means for latching said pair of doors to said bar, said pair of doors and bar having portions adapted to contact to limit the outward swinging movement of said doors.

3. A heater comprising a stove having a fuel door and an ashpit door, a casing surrounding the stove and having an opening to expose said doors, a pair of doors hingedly 40 connected with the casing at the opposite side edges of said opening, a bar extending across said opening intermediate said fuel and ashpit doors and having its terminals secured to the casing behind the edge portions thereof 45 at said opening, latching means carried by the pair of doors to engage said bar, and stops on said bar for the contact of the pair of doors when they are swung outwardly to limit such outward swinging movement.

In testimony whereof I hereunto affix my signature.

HENRY LANGE.
